UNITED STATES PATENT OFFICE.

HARRY A. MULVANY AND HARRY E. KENNEDY, OF BERKELEY, CALIFORNIA.

ELECTRIC FURNACE.

Application filed October 5, 1921. Serial No. 505,496.

To all whom it may concern:

Be it known that we, HARRY A. MULVANY and HARRY E. KENNEDY, citizens of the United States, residing at Berkeley, in the county of Alameda and State of California, have invented new and useful Improvements in Electric Furnaces, of which the following is a specification.

This invention relates to an electric furnace, and especially to a method of supporting the electric heating elements therein.

The advantages of electricity in heat production for industrial applications; for instance in furnaces, heaters and the like, are so numerous and so generally appreciated that a summary or a rehearsal of them is though unnecessary. It would be anticipated that this method of heat production would be particularly advantageous when enamelling furnaces and the like are considered as uniformity of temperature, ease of control, absence of combustion products, and durability are the prime requisites of an enamelling furnace.

In the construction of an electric furnace or muffle kiln, it should be clearly realized that the factors upon which success depends are as follows: That the furnace must have adequate heat insulation; that heat must be generated over the entire inner surface of the furnace uniformly; that the electrical parts, and particularly the heating elements, must be so disposed as to prevent contact with the wares or articles to be enamelled, and that the temperature of the electric elements should exceed the temperature of the kiln by as small an increment as possible.

The problem of insulation is readily solved. Various high class insulating materials are on the market and sufficient thickness of walls will reduce radiation and conduction losses to a minimum.

The disposition of several electric heating elements over the entire surface of the kiln, including the arch and the floor, without interfering with their free radiation into the kiln, is not easily attained. It has been common practice to sustain and protect electric elements in varying forms of kilns by means of a refractory muffle. This arrangement has the very serious handicap of restricting the heat flow between the electric elements and the kiln. Therefore an excessive temperature results in the element and since the most durable material known for high temperatures is not stable over 2000 de-

grees Fahrenheit, such a method seriously diminishes the life of the furnace and particularly the elements. Also such refractory covering or muffle, unless made exceedingly thick, will not stand the continued jarring of heavy articles continually dropped thereon.

The object of the present invention is to generally improve and simplify furnaces of the character described, and especially to provide a furnace so constructed that adequate heat insulation may be obtained; that heat will be generated over the entire inner surface uniformly; that the metallic elements or resistors will be so disposed as to prevent contact with the wares, and that the difference in temperature between the furnace and the electric resistor elements shall be exceedingly small.

Another object of the invention is to provide a special form of interlocking brick constructed of refractory material, which when properly laid up to the form of any muffle or furnace will support an element either of the wire or ribbon type; said bricks further when laid forming a zigzag slot within the furnace chamber in which the elements are disposed and supported.

Further objects will hereinafter appear.

The invention consists of the parts and the construction, combination and arrangement of parts as hereinafter more fully described and claimed, having reference to the accompanying drawings, in which—

Fig. 1 is a cross section of the furnace.

Fig. 2 is a central, vertical, longitudinal section.

Fig. 3 is a plan view of two bricks showing the position of the heating elements with relation to the same.

Fig. 4 is a cross section on line 4—4, Fig. 3.

Fig. 5 is a perspective view of one of the bricks.

Referring to the drawings in detail, A indicates in general a furnace of suitable design and construction, 2 a furnace chamber formed within the same. This furnace chamber, including arch, sides and floor, is built up of a special form of refractory brick, such as illustrated in Figs. 3, 4 and 5; certain of the bricks being arched or key bricks to form a rigid roof construction and to insure perfect design and alignment of the arch. All bricks are identical in construction; the only difference being that the

bricks employed in the arch are tapered in cross section to take care of the arch structure. The bricks when placed in position form a floor 3, sides 4, and an arch or roof 5. These are well insulated with the best grade of insulating material and the entire structure is supported by an exterior shell in the usual manner as indicated at B. The exterior shell, known as the furnace frame, 10 may be designed to suit varying conditions. It should however be constructed of exceptionally heavy cast-iron and ribbed so as to give maximum strength and to prevent distortion. Heavy cast-iron arches extending 15 over the arch and bolted to the side plates may also be advantageously employed, thereby holding the furnace arch in place and in perfect alignment at all times; similarly, cast-iron legs of suitable design may 20 be disposed below the bed plate if desired. A door not here shown, which is well insulated and built with the idea of reducing heat losses to a minimum, should be provided and peep-holes may be formed adjacent 25 the door, or at any other convenient point for observation of the interior of the furnace.

The features so far described are of no material importance as far as the present invention is concerned as it is obvious that the method of insulation, or material employed, and the particular design of the exterior furnace frame, may be changed to suit varying conditions. The present invention is 30 particularly limited to the interior design of the furnace, and especially to the method of supporting and retaining the metallic resistors or heating elements. With this object in view a special form of brick, as already 35 stated, is employed. The brick is long and narrow as shown in Figs. 3, 4 and 5, and is provided with a head at each end; the heads being illustrated at 6 and 7, respectively. Formed as an integral part of 40 the head 6 is a centrally disposed web 8, the sides of which present tapering walls or reflecting surfaces as will hereinafter be described. The central web is separated with 45 relation to the head 7 by the formation of a gap 9, and a recess is formed at the lower end of the web, as at 10; a similar recess extending crosswise of the brick being formed in the head 7, as at 11. All of 50 the bricks employed are identical in design and construction, but they are reversed with 55 relation to each other when placed in position in the furnace. This reversing of the bricks is clearly illustrated in Fig. 3. The recesses 10 and 11 formed in each brick serve 60 as a support for the metallic resister or heating element which is preferably of the ribbon type, and as the bricks are reversed when placed, it is obvious that a support 65 will be provided for the heating element at each end. The reversing of the bricks and

the formation of the webs 8 with their tapering side walls 12 is of great importance as it forms a zigzag channel, as indicated at 13, for the reception of the heating element 14, which is bent to form a zigzag or similar 70 shape. It should further be noted that the channel formation appears on the inner side or surface of the bricks, and that direct communication is formed between the furnace chamber 2 and the zigzag channels. It may 75 further be stated that the depth of the channels formed between the bricks is such that the heads 6 and 7, and the webs 8 of the respective bricks, will extend a considerable 80 distance beyond the heating elements, thus protecting them against contact with the wares placed in the furnace. It should be remembered that the floor, sides and the arch, are built up of the brick illustrated, and that continuous channels will therefore 85 be formed around the entire interior surface. The bricks being placed end for end, as illustrated in Fig. 2, will form a series of annular continuous channels and each channel being provided for the reception of an 90 element.

Electrically, the construction consists of a suitable number of circuits in multiple, one-half of which may be located in the arch of the furnace, and one-half in the floor, so 95 that in effect the heating area consists of a plurality of rings encompassing the kiln. These circuits are connected to bus-bars which are in turn attached to the secondary side of a variable voltage transformer. In 100 actual practice energy at approximately 2300 volts is employed. By means of magnetic switches connected to transformer taps, it is possible to quickly vary the furnace input. The arrangement permits of 105 very accurate adjustment of the current flow, thus suiting the needs of the individual enameller, etc.

The heating elements, as previously 110 stated, are ribbon shaped in cross section and zigzag in formation. They consist of heavy nickel chromium metal and as they are placed in the grooves or channels formed between the refractory bricks, it is obvious 115 that their heating efficiency should be great due to the large surface presented, and also because the bricks have a high dielectric strength when the average working temperature is considered, and they at the same time possess the quality of a good heat conductor under such conditions. Each brick furthermore presents a pair of inclined reflecting surfaces which materially assists in projecting or radiating the heat developed. In fact each brick may be glazed or otherwise 120 treated to further promote such effect. Direct communication between the heating elements and the furnace chamber is of great 125 importance as interference with free radiation is positively avoided.

In the construction of high temperature electric furnaces, employing metallic resistors, it becomes a necessity when successful operation is considered that the difference in temperature of the furnace and the electric resister element shall be small, that is in a furnace designed to operate at 1800 degrees Fahrenheit, the temperature of the metallic resister should not exceed 1900 degrees Fahrenheit at any point. Due to the physical properties of metallic resistors now obtainable, it is obvious that if the foregoing temperature, to-wit, 1900 degrees Fahrenheit, is exceeded, the life of the element will be comparatively short. The present construction allows an almost unrestricted radiation into the furnace chambers; in fact actual practice has determined that the temperature of the elements at their hottest points does not exceed the furnace chamber temperature by more than 60 degrees Fahrenheit and as the average furnace temperature seldom exceeds 1750 degrees Fahrenheit, it can readily be seen that the element temperatures are very conservative and productive to long life.

In most furnaces in use today, it has been common practice to sustain and protect the electric elements by means of a refractory muffle. This arrangement has a very serious handicap of restricting the heat flow between the electric element and the kiln or furnace chamber, therefore excessive temperature results in the element, and since the most durable material known and in use today, to-wit, nickel chromium, is not stable above 2000 degrees Fahrenheit, such covering or protection of the elements will obviously rapidly diminish the life of the elements. Also such refractory covering, unless made exceedingly thick, will not stand the continued jarring of heavy articles dropped on their red hot surfaces.

In the present instance by the use of the specially designed brick, it is possible to design a furnace for any use desired; the bricks when properly laid permitting elements of either wire or ribbon type to be employed, and as the elements are laid both in the floor, sides and arch of the furnace, it can readily be seen that uniform heating will be obtained. The zigzag channels formed between the bricks are so deep that the elements are amply protected, and the ware or other material to be treated in the furnace can therefore be freely inserted and removed without danger of contacting with the elements. The special brick employed furthermore permits the elements to be readily inserted or removed whenever desired and accidental release or removal is prevented by filling the gap 9 with a temporary plug of fire-clay or the like which rapidly hardens when in place.

The furnace can be so well insulated that

the workers are in comparative comfort, and as the furnace floor is built upon a solid foundation, it is obvious that sagging or distortion thereof cannot take place. This feature cannot be too strongly emphasized; for instance where oil fire furnaces are employed continual sagging of the floor and consequent warping of the bricks takes place and often results in distorted ware and continual furnace repair, this being due to the excessive heat to which the floor is exposed.

The life of the brick work in the present instance is unlimited because the heat is generated directly within the walls of the kiln and not exterior thereof, therefore, it is not necessary to maintain the excessive temperatures which are so disastrous to brick work. The speed with which operating temperatures are reached, is another valuable feature as actual experience has shown that the furnace may readily be brought from room temperature to 1700 degrees Fahrenheit in five hours without an abnormal expenditure of energy, and without causing excessive expansion to the brick work which might prove destructive.

Having thus described our invention, what we claim and desire to secure by Letters Patent is—

1. In a furnace of the character described, a brick lining, each brick of said lining consisting of a base portion, a head at each end thereof, a central web extending between the head members and forming a part of one of the head members, said web being separated and notched with relation to the opposite head member, said bricks when placed in the furnace being alternately reversed, said webs when the bricks are reversed forming zigzag channels between the bricks, and a heating element of zigzag formation adapted to be placed in the channels and supported at opposite ends by the notched portion of each brick.

2. In a furnace of the character described, a brick lining, each brick of said lining consisting of a base portion, a head at each end thereof, a central web extending between the head members and forming a part of one of the head members, said web being separated and notched with relation to the opposite head member, said bricks when placed in the furnace being alternately reversed, said webs when the bricks are reversed forming zigzag channels between the bricks, and a heating element of zigzag formation adapted to be placed in the channels and supported at opposite ends by the notched portion of each brick, the side walls of said webs being tapered to form reflecting surfaces.

3. In a furnace of the character described, a brick lining therefor composed of bricks having recesses formed on their side faces and in one end which, when the bricks are

alternately reversed and in place, form zig-zag communicating channels on the inner surface of the furnace, heating elements disposed in said channels, and means on the 5 bricks for securing the elements in the channels.

4. In a furnace of the character described, a lining for the floor, sides and roof of the furnace composed of bricks and each brick 10 consisting of a base portion, a head portion at each end thereof, a central web forming a part of one head and the base and extending to a point adjacent the opposite head, a recess formed in each brick between said last 15 named head and the web, said bricks being reversed with relation to each other when laid in the furnace, and said webs forming channels between the bricks, and heating elements disposed in said channels and supported at opposite ends by the recesses 20 formed between the webs and the heads of each brick.

5. In a furnace of the character described, a heating chamber, a lining brick for the 25 floor, sides and roof arch of said chamber, said brick comprising a base section and a head member formed on each end thereof, a narrow web extending from end to end of the brick and forming a part of one head 30 and the base portion, and a recess formed between the web and the other head.

6. In a furnace of the character described, a heating chamber, a lining brick for the floor, sides and roof arch of said chamber, 35 said brick comprising a base section and a head member formed on each end thereof, a narrow web extending from end to end of the brick and forming a part of one head

and the base portion, and a recess formed between the web and the other head, the sides 40 of the web presenting tapering walls.

7. In a furnace of the character described, a furnace chamber, a refractory lining therefor, said lining having a continuous zigzag shaped groove formed in its inner face, a 45 zigzag shaped heating element adapted to be received by the groove, and inwardly projecting knobs formed in the zigzag groove to support the heating element and to permit removal thereof without disturbing the 50 refractory lining.

8. In a furnace of the character described, a furnace chamber, a permanent refractory lining therefor, said lining having a continuous zigzag shaped groove formed in its inner face, a zigzag shaped heating element adapted to be received by the groove, and means for retaining the element in the 55 groove, said zigzag groove being tapered in cross-section so that the side faces of the 60 groove may present angularly disposed reflecting surfaces.

9. In a furnace of the character described, a furnace chamber, a permanent refractory lining therefor, said lining having a continuous zigzag shaped groove formed in its inner face, a zigzag shaped heating element adapted to be received by the groove, and inwardly projecting knobs formed in the 65 zigzag groove at opposite ends thereof to 70 support the heating element and to permit removal thereof without disturbing the refractory lining.

HARRY A. MULVANY.
HARRY E. KENNEDY.
